(57) **CLAIM**

The ornamental design for a vent and diffuser for vehicle or replica thereof, as shown and described.

DESCRIPTION

FIG. 1 is a front perspective view of a vent and diffuser for vehicle or replica thereof in accordance with the present design;

FIG. 2 is a front elevation view thereof;

FIG. 3 is another front perspective view thereof;

FIG. 4 is a right side elevation view thereof;

FIG. 5 is a rear perspective view thereof; and,

FIG. 6 is a top plan view thereof.

Portions of the vehicle shown in evenly spaced broken lines depict environmental structures that form no part of the claim. Portions of the vent and diffuser shown in dot-dash lines depict an unclaimed boundary between claimed and unclaimed portions of the vehicle.

Any combination of the illustrated features may be claimed in this application or a continuing application claiming priority to this application by converting any of the solid lines to broken lines, any of the broken lines to solid lines, or any combination thereof.
